US0D1019675S

(12) **United States Design Patent** (10) **Patent No.:** **US D1,019,675 S**
(45) **Date of Patent:** **** Mar. 26, 2024**

(54) **DISPLAY SCREEN OR PORTION THEREOF WITH GRAPHICAL USER INTERFACE**

(71) Applicant: **MEDTRUM TECHNOLOGIES INC.**,
Shanghai (CN)

(72) Inventor: **Cuijun Yang**, Shanghai (CN)

(73) Assignee: **MEDTRUM TECHNOLOGIES INC.**,
Shanghai (CN)

(**) Term: **15 Years**

(21) Appl. No.: **29/813,479**

(22) Filed: **Oct. 29, 2021**

(51) LOC (14) Cl. **14-04**

(52) U.S. Cl.

USPC **D14/485**

(58) **Field of Classification Search**

(57) **CLAIM**

The ornamental design for a display screen or portion thereof with graphical user interface, as shown and described.

DESCRIPTION

The FIGURE is an image of a display screen or portion thereof with graphical user interface showing my new design.

The outermost dot-dash broken line illustrates a display screen or portion thereof and forms no part of the claimed design. The remaining dash-dash broken lines illustrate the graphical user interface and form no part of the claimed design.

1 Claim, 1 Drawing Sheet
